UNITED STATES PATENT OFFICE.

WALTER L. WIDLAR, OF LAKEWOOD, OHIO, ASSIGNOR TO THE JIFFY JACK COMPANY,
OF CLEVELAND, OHIO, A CORPORATION OF OHIO.

JACK.

1,241,591.

Specification of Letters Patent.

Patented Oct. 2, 1917.

Application filed October 20, 1916. Serial No. 126,708.

To all whom it may concern:

Be it known that I, WALTER L. WIDLAR, a citizen of the United States, residing at Lakewood, in the county of Cuyahoga and State of Ohio, have invented a certain new and useful Improvement in Jacks, of which the following is a full, clear, and exact description, reference being had to the accompanying drawings.

10. This invention relates generally to lifting jacks and more particularly to one designed for automobile use, and the object of the invention is to provide a cast metal jack which will be inexpensive, very light and durable, 15 exceedingly easy and accurate in its operations, and one which will permit the load to be raised or lowered step by step with ease and rapidity.

Another object is to provide a step by step 20 jack in which only one spring is employed and a still further object is to provide a jack in which the lifting bar can be pulled out to its maximum height, or dropped back instantly, when desired.

25. With these various objects in view the invention consists in the novel features of construction and the manner of arranging the same, all of which will be fully described hereinafter and pointed out in the claims.

30. In the drawings forming a part of this specification, Figure 1 is a perspective view of a cast metal lifting jack embodying one form of my invention; Fig. 2 is a sectional elevation illustrating the positions of the 35 parts at the start of the lifting movement; Figs. 3 and 4 are similar views showing the positions of the parts at subsequent stages of the lifting operation; Figs. 5, 6, 7 and 8 are similar views showing the various 40 positions of the parts during the various stages of the lowering operation; Fig. 9 is a transverse sectional view on the line 9—9 of Fig. 2, and Fig. 10 is a view illustrating in perspective the lever, pawls, cam, shifting lever 45 and pivot connection all detached and separated.

In the practical embodiment of my invention I employ a hollow cast metal standard 10, having a flat base 11 integral therewith;

and working in the hollow standard 10 is the 50 lift bar 12 having a curved head 13. The lift bar is provided with ratchet teeth 14 in the forward face.

The standard 10 is made with a forwardly projecting housing 10^a in which is pivoted 55 the operating lever 15 upon the pin or bolt 16, the outer end of the lever being socketed or hollow to receive the wooden handle 17. The inner end of the lever 15 is bifurcated as shown at 18 and between the members are 60 pivoted the working pawl 19 and the holding pawl 20, the holding pawl 20 being pivoted upon the pin or bolt 16 while the pawl 19 is pivoted at the extreme inner end of the lever and therefore has the power communicated thereto through the lever.

One of the members 18 has a circular boss 18^a surrounding the pivot opening and this circular boss serves as a pivot for the cam plate 21 which is slotted at 22 providing a 70 finger 23 and a head 24 and this cam plate 21 also has a rectangular shaped opening 25 adjacent the end of the slot 22. A laterally projecting lug 26 is arranged adjacent the pivot opening of the cam plate and in substantial alinement with said pivot opening and the slot 22. The working pawl 19 carries a laterally projecting pin 27 which is adapted to work in the slot 22, and the holding pawl 20 has a laterally projecting pin 80 28 which works in the rectangular shaped opening 25 in a manner hereinafter explained.

A shifting lever 29 is also pivoted upon the boss 18^a, this lever having a notch 30 adapted to straddle the lug 26 and the inner end of this shifting lever is connected to a spring 31 having a central core, the opposite end of the spring being securely fastened at 32 at the lower end of the housing 10^a.

90
95
The operation of the parts is as follows. In order to lift a load through the medium of the lifting bar, the shifting lever 29 is thrown upwardly as shown in Figs. 1, 2, 3 and 4 and the lever is worked up and down on the pivot 16. The working pawl 19 engages the ratchet face of the lifting bar and causes the bar to be moved upwardly at

each downward movement of the lever and when the lever completes its downward movement and starts back on the return movement, the holding pawl by pin 28 in 5 opening 25 will be brought into engagement with the ratchet face of the lifting bar and hold the same while the working pawl is moved out by finger 23 and carried downwardly to obtain a lower engagement with 10 the lifting bar, and these operations are continued until the load has been lifted to the desired extent.

When it is desired to lower the load, step 15 by step, the shifting lever 29 is thrown downwardly as indicated in Figs. 5, 6, 7 and 8 and it will be understood that as the lever 29 is moved from one position to another the cam plate 21 is also shifted by the engagement of the lug 26 with the notched portion 20 30 of the shifting lever and the spring 31 will hold the cam plate in either one of its adjusted positions.

The shifting lever 29 having been thrown down, the hand lever 15 is worked down 25 and up, being moved down to obtain a grip and up to lower the bar with the load thereon. Fig. 5 illustrates the position just prior to the shifting of the load from the holding pawl 20 to the working pawl 19, and Fig. 6 30 illustrates the lowermost position of the hand lever 15 wherein the load has been shifted entirely from the holding pawl 20 to the lowering pawl 19. The holding pawl 20 is released by the pull of the spring 31 35 just as soon as the working pawl 19 assumes the load. Fig. 7 illustrates the position of the parts just prior to the shifting of the load from the working pawl 19 to the holding pawl 20, the pin 27 of the pawl 19 coming 40 into engagement with the finger 23 of the cam plate and thereby actuating the cam in a counterclock wise direction against the pull of the spring 31 and permitting the holding pawl 20 to drop into engagement 45 with the lifting bar. Fig. 8 illustrates the maximum elevated position of the hand lever 15 wherein the holding pawl 20 has assumed the entire load and the pawl 19 is kicked out of the path of the ratchet teeth 50 by the finger 23, the cam and its finger 23 being at all times biased in a clockwise direction. The holding pawl 20 holds the lifting bar in this position while the hand lever 15 is being again lowered to the position 55 shown in Figs. 5 and 6 where the working pawl 19 is caused to take a fresh lowering grip, the operations being continued until the lowering of the load is complete.

It will thus be seen that I provide an exceedingly strong, simple and durable jack and one which can be quickly and easily adjusted for either raising or lowering a load step by step.

It will also be understood that the lifting

bar, with no load thereon, can be instantly 65 dropped when desired by throwing down the shifting lever and working the hand lever. The lifting bar can also be pulled out to its maximum height at any time. Thus 70 it will be seen that the jack is a quick acting one in both directions.

Having thus described my invention, what I claim is:—

1. In a device of the kind described, the combination with a standard, of a lifting member movable therein, a lever pivoted thereto, a holding pawl connected to the lever pivot, a working pawl connected to the end of lever, a shiftable cam having a finger adapted to engage the working pawl, said cam also having an opening adapted to receive a pin carried by the holding pawl, and a spring actuated shifting lever adapted to engage said cam and in one position bias the holding pawl toward said lifting member and in the other position bias the same in the opposite direction. 75 80 85

2. In a device of the kind described, the combination with a standard, lifting bar and lever, of a working pawl connected to the end of said lever, a holding pawl arranged upon the lever pivot, said pawls having laterally projecting pins, a cam arranged upon the lever pivot and having an opening and a slot adapted to receive respectively the pins of the holding and working pawls, and a spring actuated shifting lever mounted also upon the lever pivot, said shifting lever being adapted to engage the cam and in one position bias the holding pawl toward said lifting member and in the other position bias the same in the opposite direction. 90 95 100

3. In a device of the kind described, the combination of a standard, of a lifting member movable therein, a lever pivoted thereto, a holding pawl connected to the lever pivot, a working pawl connected to the end of said lever, a cam and a shifting lever also mounted upon the lever pivot, said pawls having lateral projections adapted to engage said cam, said cam having a finger, a head, and an opening adjacent said head, and a slot between said finger and head, said cam also having a lateral projection adapted to engage the shifting lever, and a spring having one end connected to said shifting lever, the opposite end being secured to the standard. 105 110 115

4. In a device of the kind described, the combination with a standard, of a lifting member movable therein, a lever pivoted thereto, a holding pawl connected to the lever pivot, said holding pawl having thereon a laterally projecting pin, a working pawl connected to the end of lever, a shifting cam having a finger adapted to engage the working pawl, said cam also having a lost motion connection with the pin on said hold- 120 125

ing pawl, and a spring actuated shifting lever having a lost motion connection with said cam, said shifting lever being adapted in one position to bias said cam and said holding pawl toward the lifting member and in the other position to bias them in the opposite direction.

In testimony whereof, I hereunto affix my signature in the presence of two witnesses.

WALTER L. WIDLAR.
